SCHOOL TRAILER

Wade H. Gowl, Baltimore, Md., assignor to American Trailer Co., Inc., Washington, D. C., a corporation of Delaware

Application October 23, 1956, Serial No. 43,493

Term of patent 14 years

(Cl. D14—3)

I claim:

The ornamental design for a school trailer, as shown.
